UNITED STATES PATENT OFFICE

2,462,119

GAS REGULATING DEVICE FOR FIREARMS

Cyril A. Moore, Springfield, Mass., assignor to the
United States of America as represented by the
Secretary of War

Application June 28, 1946, Serial No. 680,106

6. Claims. (Cl. 89—193)

(Granted under the act of March 3, 1883, as
amended April 30, 1928; 370 O. G. 757)

1 2

ed herein may be manufactured in accordance with the process of Fig. 2 is a section

1

The invention described herein may be manufactured and used by or for the Government for governmental purposes, without the payment to me of any royalty thereon.

This invention relates to improvements in an automatic firearm wherein the firing mechanism is operated by means of explosive gases which are allowed to escape from the barrel and act against a movable piston and is directed more particularly to a gas regulating device for such a firearm whereby the energy imparted by the actuating gases impinging on the piston is regulated.

Control of these explosive gases in such a firearm is very desirable not only to allow for the fluctuation of the pressures of the escaping gases but also to eliminate in so far as possible the inevitable accumulation of powder residue and carbon attendant with the actuating gases. In other words, when the powder residue and carbon deposit become such that the firearm becomes fouled up so that the efficiency of the weapon is impaired, it is desirable to step up the power thereof and make it possible for an increased volume of actuating gases to escape from the barrel so as to exert greater energy on the piston.

Accordingly, it is a principal object of this invention to provide an apparatus for controlling the energy imparted by the actuating gases of gas-operated firearms and at the same time substantially eliminating any accumulation of powder residue and carbon within the gas cylinder. For purposes of convenience in description, the gas regulating means of the invention is shown as utilized in a United States Army Browning automatic rifle such as is disclosed in U. S. Patent No. 1,293,022 issued February 4, 1919, to John M. Browning.

It is a further object of the invention to provide a gas regulating device which is easy to assemble in the firearm and facile of removal for purposes of cleaning as is desirable and necessary from time to time. Other features are that the device is simple in form, economical to manufacture, and requires no modification in the existing construction of the firearm with which it is to be associated.

The specific nature of the invention as well as other objects and advantages thereof will clearly appear from a description of a preferred embodiment as shown in the accompanying drawings in which:

Fig. 1 is a partial sectional view through the construction of the invention:

Fig. 2 is a sectional view on the line 2-2 of Fig. 1.

Fig. 3 is a side elevational view, partly in section:

Fig. 4 is an end view of the adjusting member; and

Fig. 5 is a sectional view on the line 5—5 of Fig. 3.

There is a gas cylinder tube 2 suitably associated with a barrel 4 and a cooperating piston 5 is slidably mounted within the cylinder 2. A gas port 6 provided in the tube 2 is in alignment with a gas port 7 provided in the barrel 4.

15 There is a hollow lock-screw member 10 comprising a rear shank part 16, an integral cylindrical head part 14, and an exteriorly-threaded portion 18 disposed between shank part 16 and head part 14 for threadedly engaging the usual threads provided in the forward end of tube 2.

20 A locking washer 20 is provided intermediate said portions 18 and 14 and its greatest diameter is slightly greater than the outside diameter of tube 2. While the washer 20 may take any desired shape, it is shown

25 sired shape, it preferably consists of a more or less horseshoe shaped member disposed in a suitable annular groove 22 provided in lock-screw member 19 just rearwardly of part 14. Thus portions of the washer 20 may be bent rearwardly to engage in the notches which are usually provided in the forward end of the tube whereby the screw member is securely fixed in association with the gas cylinder.

There is provided a cylindrical adjusting member 32 comprising a cylindrical rear shank part 32 which, it will be noted, is unthreaded and relatively smooth surfaced. This shank part 32 is provided with two or more ports radially disposed of varying diameters and, while in the drawings, three such ports 34, 36, and 38 are shown communicating with an axial hole 66 therein, it will be understood that the exact number of such ports is unlimited.

set of such ports is unlimited. The lock screw 10 is also provided with an exterior annular groove 26 disposed rearwardly of threaded portion 18 and there is a gas port or hole 27 which extends into the groove 26 and through to the bore of the hollow lock screw member 10. It is this port 27 which aligns with one of the ports 34, 36, and 38 of adjusting member 30 and by virtue of the groove 26 there will be communication with the gas port 6 in the tube 2 as well as with the port 7 in the barrel 4. The groove 26 makes it unnecessary to qualify the port 27 with port 6.

member 10 is interiorly threaded for threadedly engaging an exteriorly-threaded portion 40 of the adjusting member 30, which part 40 is in all cases located forwardly of the apertures or ports above-mentioned in the shank part 32. It is these ports that will be selectively aligned with the gas port 27 of lock screw 10, and thereby, of course, communicate with the ports 6 and 7 of the barrel and gas cylinder by virtue of groove 26.

The forward end portion of the adjusting member 30 is enlarged to provide a hollow head portion 42 and has a knurled surface, as indicated, to facilitate rotation of the adjusting member 30 with respect to the lock screw member 10. Spring pressed means are provided to urge the adjusting member forwardly and in counteraction of the screw threads of the lock screw and adjusting members. This may consist of a pin or plunger 54 seated in a suitable socket or recess 52 and adapted to engage in one of the recesses provided in the forward face of the head part 14, with a coil spring 53 of conventional form disposed around and suitably engaging the pin 54.

The forward face of the lock screw member's head is provided with a plurality of spaced recesses therein for receiving the pin 54. In addition, the adjusting member 30 is also provided with some position-indicating means, such as spaced indentations 60 on the periphery of its head portion 42 or other easily applied markings adapted to align with similarly spaced markings 62 provided on the head part 14 of the lock screw member 10. That is to say, as the adjusting member 30 is rotated relative to the lock screw member 10, the respective markings 60 and 62 thereof may be caused to come into alignment according to the adjustment desired and these will indicate the particular port desired.

The adjustment member 30 is also provided with a gas breather orifice 65 communicating with axial hole 66 and the hole of head portion 42 to prevent excessive fouling and the accumulating of powder residue and carbon within the cylinder.

When the parts are in assembled position, the threads thereof are disposed at a distance forwardly of all of the gas-escape ports previously mentioned. As a result, the powder and carbon deposits are not so apt to foul the threads, as inevitably happens in the construction heretofore known. In addition the residual gases with this deleterious matter may escape through the breather orifice after the piston has been propelled rearwardly. Thus the construction of the invention obviates the usual frequency of removal, cleaning, and replacement of parts.

If desired, the head 42 of the adjustable member 30 may be provided with one or more recesses or holes 64 in the side or sides thereof adapted to receive an instrument (such as the end of a cartridge which is always supposed to be convenient) to be utilized as a wrench to facilitate rotation of the member. This provision is desirable for the reason that the various parts of the mechanism necessarily become quite hot after repeated firing of the weapon and are therefore difficult to handle.

I claim:

1. A gas-regulator device for a gas-operated firearm comprising in combination, a cylindrical lock-screw member having a bore therethrough insertable in the gas-cylinder tube of the firearm and adapted to be secured therein, said lock-screw member being provided with an exterior annular groove having a gas port extending

radially therethrough communicating with said bore, and an adjusting member having an axial hole therethrough rotatably and removably disposed within said bore of said lock-screw member and including a rear shank portion which is provided with a series of ports therein communicating with said axial hole, all adapted and arranged whereby said adjusting member may be rotated so that said ports thereof may be selectively aligned with said gas port of said lock-screw member.

2. A gas-regulating device for a gas-operated firearm comprising in combination, a cylindrical lock-screw member having a bore therethrough insertable in the gas-cylinder tube of the firearm and provided with a threaded portion whereby the same may be secured therein, said lock-screw member being formed to have an exterior annular groove and provided with a gas port extending therethrough and which is disposed rearwardly of said threaded portion and extends radially through the grooved portion communicating with said bore, and an adjusting member having an axial hole therethrough rotatably and removably disposed in said bore of said lock-screw member, said adjusting member including a relatively smooth-surfaced rear shank portion which is provided with a series of ports therein communicating with said axial hole, all adapted and arranged whereby said adjusting member may be rotated so that said ports thereof may be selectively aligned with said gas port of said lock-screw member.

3. A gas-regulating device for a gas-operated firearm comprising in combination, a cylindrical lock-screw member with a bore therethrough insertable in the gas-cylinder tube of the firearm and arranged to be secured therein, said lock-screw member including a forward end portion provided with internal screw-threads and a rear end portion which is provided with a gas port in its side leading into said bore thereof, and an adjusting member with an axial hole therethrough including an intermediate portion threadably engaged within said forward end portion of said lock-screw member so as to be rotatable relative thereto and an integral rear end portion which extends into said bore of said rear end portion, said rear end portion of the adjusting member being provided with a plurality of spaced ports leading into said axial hole for selectively communicating with said gas port of said lock-screw member.

4. A gas-regulating device for a gas-operated firearm comprising in combination, a cylindrical lock-screw member with a bore therethrough threadably engaged within the forward end portion of the gas-cylinder tube of the firearm and provided with a radial gas port located at a distance rearwardly of the threads thereof, and an adjusting member with an axial hole therethrough removably disposed within said lock-screw member including a forwardly disposed portion which is threadably engaged with the forward end portion thereof so as to permit rotation of the members relative to one another and a rearwardly disposed portion which is provided with a plurality of spaced ports leading into said axial hole adapted to be selectively aligned with said gas port according to the degree of rotation of said adjusting member relative to said lock-screw member.

5. A gas-regulating device for a gas-operated firearm comprising in combination, a cylindrical

lock-screw member having a bore therethrough arranged to be threaded into the forward end portion of the gas-cylinder tube of the firearm and having a grooved portion therein located rearwardly of the threads thereof, said grooved portion being provided with a gas-escape port in a side thereof leading into said bore, and an adjusting member having an axial hole therethrough removably disposed within said lock-screw member and including a rear end portion of relatively reduced diameter and an intermediate portion which is exteriorly threaded and a forward end portion, said intermediate portion being threadedly engaged in said lock-screw member, said forward end portion being arranged to facilitate a relative rotation of the members, said rear end portion being relatively smooth-surfaced and provided with a plurality of spaced ports leading into said axial hole adapted to be selectively aligned with said gas-escape port.

6. A gas-regulating device for a gas-operated firearm comprising in combination, a cylindrical lock-screw member having a bore therethrough insertable in the gas cylinder tube of the firearm and provided with a threaded portion whereby the same may be secured therein, said lock-screw member being formed to have an exterior annular groove and provided with a gas port extending therethrough and which is disposed

rearwardly of said threaded portion and extends radially through the groove portion communicating with said bore, and an adjusting member rotatably and removably disposed in said bore of said lock-screw member, said adjusting member being provided with an axial hole therethrough terminating in a restricted orifice in the forward end thereof to permit powder residue and carbon attendant with actuating gases to escape therefrom, said adjusting member including a relatively smooth surfaced rear shank portion which is provided with a series of ports therein communicating with said axial hole, all adapted and arranged whereby said adjusting member may be rotated so that said ports thereof may be selectively aligned with said gas port of said lock-screw member.
